(57) **CLAIM**

The ornamental design for a safety wear plate for firearm as shown and described.

DESCRIPTION

FIG. 1 is a perspective view of a safety wear plate for firearm showing the new design;

FIG. 2 is a perspective view of the safety wear plate shown in FIG. 1;

FIG. 3 is a left side view of the safety wear plate shown in FIG. 1;

FIG. 4 is a right side view of the safety wear plate shown in FIG. 1;

FIG. 5 is a top view of the safety wear plate shown in FIG. 1

FIG. 6 is a bottom view of the safety wear plate shown in FIG. 1;

FIG. 7 is a front view of the safety wear plate shown in FIG. 1; and,

FIG. 8 is a rear view of the safety wear plate shown in FIG. 1.

The broken lines are included for the purpose of illustrating features that form no part of the claimed design.
